(57) **CLAIM**

The ornamental design for a shoe, as shown and described.

DESCRIPTION

FIG. 1 is a front perspective view of a shoe showing our new design;
FIG. 2 is a side view thereof;

FIG. 3 is a rear perspective view thereof;

FIG. 4 is a rear view thereof;

FIG. 5 is an opposite side rear perspective view thereof;

FIG. 6 is an opposite side view thereof; and,

FIG. 7 is an opposite side front perspective view thereof. The uneven-length broken lines immediately adjacent to the shaded areas define the bounds of the claimed design and form no part thereof. The zigzag-shaped even-length broken line within the shaded area on the downwardly extending tab represents stitching which forms no part of the claimed design. The uneven-length broken lines depicting the remainder of the shoe show features that form no part of the claimed design.
